UNITED STATES PATENT OFFICE.

LEON JARUSZ, OF MILWAUKEE, WISCONSIN.

FLOOR-CLEANER.

1,252,806.

Specification of Letters Patent.

Patented Jan. 8, 1918.

Application filed January 10, 1917. Serial No. 141,519.

To all whom it may concern:

Be it known that I, LEON JARUSZ, a citizen of the United States, resident of Milwaukee, county of Milwaukee, and State of Wisconsin, have invented certain new and useful Improvements in Floor-Cleaners, of which the following is a specification.

This invention relates to improvements in floor cleansing and scrubbing machines, and 10 has as its principal object the provision of an apparatus which may be readily operated in the manner of a carpet sweeper, and which comprises devices for moistening the surface passed over, collecting and dispensing 15 of the accumulations and of thoroughly cleansing and brushing the floor or carpet.

These and other like objects are attained by the novel design, construction and combination of parts hereafter described and 20 shown in the accompanying drawings, forming a part of this disclosure, and in which:—

Figure 1 is a side elevational view showing an embodiment of the invention.

Fig. 2 is a vertical sectional view of the 25 same, and

Fig. 3 is a rear view thereof.

The apparatus consists of a pair of tanks 10 and 11, located respectively at the front and center of the apparatus, the walls of 30 which consist of a pair of uniformly shaped side supports having longitudinally disposed lower members 14 and integrally formed, front slanting raised elements 15 and 16, the sides being supported upon shafts 35 17 and 18 respectively at the front and rear of the apparatus. These shafts have mounted upon them wheels 20 and 21, provided with rubber tires adapted to engage with the surface passed over, causing the wheels to 40 rotate as the apparatus is moved in either direction.

Affixed upon the front axles 17 are spur gears 23 communicating rotary motion to a train of gears comprised of spur pinions 24, 45 25, and 26, two of which are fixed rigidly upon transverse shafts 28 and 29 rotatably mounted in the frames 14 and having upon them cylindrical brushes 30 and 31 the latter of which is at the extreme front of the 50 apparatus, the gears 25 acting as idlers in transmitting motion.

The tank 10 is formed with compartments 55 35 and 36 respectively upper and lower, the lower compartment being filled through a 55 spout 37 with water or other cleansing solution which is dispensed normally through a

plurality of minute perforations 38 formed at the front through the bottom wall, the openings being controlled by a slide or gate valve 39.

Thus water may be dispensed from the compartment 36 directly upon the brush 31 so as to moisten the surface over which the machine is passed, the brush acting to distribute the water, the action being followed 65 by the second and larger scrubbing brush 30, so as to loosen any adhering accumulations.

Mounted in the frame sides 15 are shafts 40, 41, and 42, carrying sprockets 44, 45, and 46, by means of which the chain 47 is driven 70 through a pinion 43 on the shaft 42, the teeth of the pinion engaging with the gear 23.

Secured to the chain at regular intervals are a plurality of flexible wipers 48, adapted to lick up the accumulations loosened by the 75 brush rollers and at the same time convey them to the upper part of the machine, eventually disposing the detritus within the compartment 35 where it may be removed by raising the cover 49 at desired intervals. 80

Similarly, the tank 11 is provided with compartments 50 and 51, the latter being provided with a receiving spout 52, accessible through the removable cover 53 of the tank. The contents of the lower compartment 51 85 may be dispensed through minute perforations 55 controlled by the gate valve 56 so as to sprinkle the surface, which is further cleansed by the rubbing action of the flexible wipers 58 attached to the chain 59 carried by 90 sprockets 60 61 and 62 mounted upon the shafts 63, 64, and 65.

A spur gear 66 is fastened upon the shaft 64 and driven through a gear 67 secured upon the shaft 18 whereby the chain and 95 wipers are caused to operate, cleansing the surface and conveying the accumulations into the compartment 50, from whence it may be readily removed.

The apparatus is operated through the 100 "U" shaped frame 70 pivotally engaged at the front of the machine and provided with an operating handle 71 by which the apparatus is manipulated.

Both tanks 10 and 11 have upon their exterior, clips 73 and 74, adapted to engage with angularly disposed projections 75 and 76 extending upward from the side plates 14 so that the tanks may be readily removed by raising the same when it is desired to 110 clean them.

The operation of the apparatus is thought

to be evident from the foregoing, and from which it will be seen that an effective device is provided for thoroughly cleansing, scrubbing, and removing any accumulations 5 which it may be desired to remove from a floor or the like. Obviously a carpet may be cleaned without raising dust and it will be evident that solutions of an antiseptic nature may be dispensed by the apparatus.

10 Having thus described my invention, what I claim as new, and desire to secure by Letters Patent, is:—

A floor cleaning machine comprising a wheeled frame, a pair of partitioned tanks 15 mounted respectively at the front and rear of said frame, each tank having upper and lower compartments and an inclined rear wall having an opening near the top to the upper compartment therein, means for re-

movably engaging said tanks with said frame, means for filling the lower compartments in said tanks independently of the upper compartment, a pair of rotatable roller brushes under the foremost of said tanks, means for delivering the contents of the lower compartment of said foremost tank to one of said pair of roller brushes, means for dispensing the contents of the lower compartment in the rear tank, endless wiper carriers engaging the inclined walls of said tanks, means for the actuation of said carriers, and means combined with said wiper carriers for conveying accumulations to the mentioned openings to the upper compartments in both of said tanks. 20 25 30 35

In testimony whereof I have affixed my signature this 14th day of December, 1916.

LEON JARUSZ.

Copies of this patent may be obtained for five cents each, by addressing the "Commissioner of Patents, Washington, D. C."
